UNITED STATES PATENT OFFICE.

KARL GRIENAUER, OF NEW YORK, N. Y.

STRINGED MUSICAL INSTRUMENT.

SPECIFICATION forming part of Letters Patent No. 703,572, dated July 1, 1902.

Application filed March 29, 1902. Serial No. 100,520. (No model.)

To all whom it may concern:

Be it known that I, KARL GRIENAUER, a citizen of Austria-Hungary, and a resident of New York city, county and State of New York, have 5 invented certain new and useful Improvements in Stringed Musical Instruments, of which the following is a specification.

This invention relates to a stringed musical instrument so constructed that the resonating-chamber is placed under transverse tension in addition to the longitudinal tension imparted by the strings. By this transverse tension the quantity as well as the quality of the tone is greatly improved.

15 In the accompanying drawings, Figure 1 is a perspective view of a violoncello provided with my improvement; Fig. 2, a cross-section on line 2 2, Fig. 1. Figs. 3 to 5 are details of the brace and nut, and Fig. 6 a cross-section 20 of a modification.

The letter *a* represents the belly, *b* the back, and *c* the sides, of the resonating-chamber of a stringed musical instrument, such as a violin, viola, violoncello, or bass.

25 The strings *d* subject the belly *a* and back *b* to high longitudinal tension, but not to transverse tension. In order to also subject them to transverse tension, I fit into the resonating-chamber a number of transverse braces 30 *e*, extending in planes at right angles to the strings. These braces are arranged, preferably, diagonally, as shown in Fig. 2, extending from one upper point to the transversely-opposite lower point. Along one edge of the

35 resonating-chamber the usual bead *f* is slotted or mutilated for the accommodation of a nut *g*, which is of oblong shape and forms, in effect, a part or continuation of the bead, Fig. 3. This nut engages the outwardly-extending threaded end of the brace *e*, and by turning it the brace may be placed under any strain desired to impart a corresponding transverse tension to the belly and back. Underneath the nut *g* a reinforcing-plate *h* may be 40 fitted. Along the other edge of the resonating-chamber the bead is also cut away to ac-

commodate a correspondingly-shaped plate *i* for engaging the headed end of the brace. By the construction described the nut *g* is exposed and accessible from the outer side of 50 the instrument, so that the tension may be readily adjusted from the exterior of the resonating-chamber.

In Fig. 6 the diagonal braces *e* are replaced by parallel transverse braces *j*, extending 55 from one side *c* to the opposite side *c*. These sides are provided with perforated reinforcing-strips *k*, through which the braces pass and which prevent the braces from tearing through or collapsing the sides. In this modification the nuts for adjusting the tension of the braces are likewise mounted upon the exposed ends of the same at the exterior of the resonating-chamber.

It will be seen that by my invention the 65 belly and back are placed under transverse tension in addition to the longitudinal tension caused by the strings. In this way the entire resonating-chamber is placed under high strain in all directions, by reason of 70 which the quality as well as the quantity of the tone is greatly improved.

What I claim is—

1. A stringed musical instrument provided with a resonating-chamber, transversely-arranged threaded braces traversing said chamber, and adjusting-nuts on the outer side of the chamber that engage said braces, substantially as specified. 75

2. A stringed musical instrument provided with a resonating-chamber, a slotted bead extending along one edge of said chamber, a pair of transverse diagonal braces, and oblong nuts engaging said braces and fitted within the bead-slots, substantially as specified. 80

Signed by me at New York city, New York, this 28th day of March, 1902.

KARL GRIENAUER.
